CARBONATOR

Eugene Schaer, Fort Frances, Ontario, Canada

Application February 29, 1940, Serial No. 321,554

4 Claims. (Cl. 261—21)

This invention relates to a carbonator which is particularly adapted for use as a device for carbonating beer and other liquids by injecting carbon dioxide gas into the liquid.

Carbonating devices now in use require a high gas pressure, thereby disturbing the colloidal structure of the liquid and causing loss of a high percentage of carbon dioxide and requiring considerable time for "after-aging" in order to get the liquid back to its original colloidal consistency.

It is, therefore, one object of the invention to provide a device by the use of which carbon dioxide gas may be injected under low pressure into a stream of liquid flowing from a tank through the carbonator to a keg, barrel, or other container.

It has also been found that since carbonators now in use only perform one charging of gas into the liquid under treatment, thus necessitating repeating the process until the right percentage of gas is obtained, much loss of time and gas as well as more labor is involved.

It is, therefore, another object of the invention to provide a device of such construction that the gas may be discharged as a series of jets and successively mixed with the liquid as it flows through the carbonator. It will thus be seen that a number of charges of gas may be injected into the liquid during a single passage of the liquid through the carbonator and thus time and labor will be conserved.

Another object of the invention is to so arrange the jets or nozzles that the gas will be discharged in opposite directions by successive jets, the jets or nozzles being further so formed that as the liquid moves through the carbonator it will be alternately diverted toward the center and toward walls of the carbonator and carbonating of the liquid thus assisted.

Another object of the invention is to so arrange the jets or nozzles and so control flow of gas through the same that the number of times gas is injected into the liquid may be controlled and also the quantity of gas discharged from the various jets or nozzles, controlled by adjustment of valves through which gas flows to the jets.

Another object of the invention is to provide a device of this character wherein the carbonated liquid is passed through a screen which causes the gas bubbles to be broken up into equal, uniform sizes surrounded by an equal side wall of colloidal matter, thus producing a creamy consistency which will last longer.

Another object of the invention is to provide a carbonator which is so constructed that its ele-

ments may be easily taken apart for thorough cleaning and sterilization and then quickly assembled for use.

The invention is illustrated in the accompanying drawings, wherein:

Fig. 1 is a side elevation of a carbonator of the improved construction.

Fig. 2 is a sectional view taken vertically through the same.

10 Fig. 3 is a sectional view taken transversely through the carbonator on the line 3—3 of Fig. 2.

Fig. 4 is a sectional view on an enlarged scale taken diametrically through the lower inlet end of the carbonator.

15 Fig. 5 is an enlarged sectional view of one of the nozzles mounted in the mixing chamber centrally thereof.

Fig. 6 is a view taken on the line 6—6 of Fig. 5.

Fig. 7 is a side elevation of a carbonator having a casing of greater depth.

This improved carbonator is for charging beer, soft drinks, and other liquids with carbon dioxide gas and has a casing consisting of an upper section 1 formed of metal, one or more lower sections 2 formed of glass tubing, and a head 3 which is also formed of metal and has an outstanding flange 4 secured against the flange 5 of the upper section 1 by screws 6. A gasket 7 forms a tight seal between the two flanges and prevents leakage when the screws are tightened.

The upper section 1 of the casing has a base 8 having a lower member 9 and the glass lower section 2 rests upon a metal base 10 having a lower section 11, and referring to Fig. 2, it will be seen that upper and lower ends of the glass section 2 are surrounded by annular flanges 12 and 13. The members 9 and 11 have threaded engagement with the members 8 and 10 and elongated bolts or rods 14, which pass through openings in

40 the base member 8 and have threaded engagement with the base member 10, serve to draw the base member 10 upwardly and firmly hold the glass tube or lower casing section 2 in place with the gaskets 15 compressed to form a tight joint.

45 The section 11 extends downwardly to form a tubular neck 16 with which a pipe leading from a tank or other source of supply, is adapted to be connected and it will be readily understood that liquid will flow from the tank into the casing through the bottom thereof and upwardly through the casing into the head 3 and out through the discharge neck 17. The section 10 is formed with a large central opening 18 and sections 8 and 9 are also formed with openings 19 and 20. In the embodiment shown in Fig. 7,

base members 21 and 22 are disposed between the glass casing sections 2, these members being similar in construction to the base members 8 and 9 except that the member 21 is formed with an upstanding annular flange 23 corresponding to the flange 13 of the member 10. It should also be noted that the rods 24 are of sufficient length to extend through the outstanding flanges of the base members 8 and 21 and have their lower ends screwed into sockets formed in the outstanding flange of the base member 10. By using additional sections 2 and base members 21 and 22, a casing of greater height may be formed.

Each base or spacer is intended to serve as a nozzle through which gas may be discharged as a film or spray into the casing. Referring to Figs. 2 and 4, it will be seen that the upper member of each nozzle has its under face formed with an annular channel 25 into which gas is to be delivered through a passage 26 formed in a thickened portion or boss extending radially of the nozzle and having a threaded socket 28 from which the passage 26 leads. A recess or depression 29 is formed in the upper face of the lower nozzle section and is spaced from the confronting portion of the under face of the upper nozzle section and provides a narrow, circumferentially extending outlet slit communicating with the channel 25 and through which gas is discharged as a flat annular thin layer directed toward the center of the casing and through which the liquid passes as it flows upwardly in the casing. The thin layer of gas will, of course, be deflected upwardly and intermingling with the liquid as the liquid flows through the casing.

There have also been provided inner nozzles 30 disposed in staggered relation to the outer nozzles. The nozzles 30 are interposed between sections 31 of a gas pipe 32 having its upper end screwed into the depending socket 33 of a tubular arm 34 carried by the head 3 and having a socket 35 at its outer end.

Each of the nozzles 30 has upper and lower sections or members 36 and 37, the upper section 36 being formed with a pocket 38 from which extend ports 39 communicating with an annular channel 40. The upper surface of the lower nozzle section or member 37 is formed with a depression or recess 41 about its periphery communicating with the channel 40 and constituting a circumferentially extending outlet slit through which gas is discharged as a flat thin layer or jet directed toward walls of the casing. The jets or thin layers of gas discharged from the nozzles travel in a direction opposite to the direction in which the jets or thin layers of gas discharged from the nozzles of the casing travel. Therefore, a very good intermingling of gas with the liquid will be effected. It should also be noted that since the nozzles 30 have flat under faces and the nozzles between the upper and lower sections of the casing also have wide under faces, the upwardly flowing liquid will be caused to travel in a tortuous path through the casing and intermingling of the gas and liquid will thus be aided.

The gas is obtained from a suitable source of supply such as a pressure tank and flows through a conduit 42 provided with a valve 43 for controlling flow of gas through the conduit. A check valve 44 controls directional flow of the gas through the conduit and, at points spaced from each other longitudinally thereof, the conduit has T-couplings 45 from which extend branch pipes 46 controlled by valves 47 and secured in

the sockets 28 and 35 by packing glands 48. By means of valves 47, flow of gas to the nozzles can be controlled and also the nozzles may be selectively set in operation for discharge of gas into liquid flowing through the casing. The gauge 49 at the top of the casing indicates the pressure of the carbonated liquid.

The carbonated liquid flows from the head through the discharge neck 17 and through the coupling 50 by means of which the neck is connected with a hose or pipe leading to a keg or barrel, or other container to be filled with the carbonated liquid. A cup-shaped screen 51 is mounted in the coupling where it is secured by an outstanding flange clamped between the coupling and the end of the neck. Since the carbonated liquid passes through the screen, gas bubbles in the beer or other liquid will be broken up into equal uniform size surrounded by an equal size wall of colloidal matter and producing foam of a solid, creamy consistency. A test coil 52 is provided at one side of the head for testing the consistency of the foam in beer or other liquid being carbonated.

Having thus described the invention, what is claimed is:

1. A carbonator comprising a chamber having an inlet and an outlet, outer nozzles in said chamber between the inlet and outlet spaced from each other longitudinally of the chamber and extending about walls of the chamber and having their inner peripheries formed with circumferentially extending outlet slits for discharging thin layers of gas toward the axial center of the chamber, a gas pipe extending longitudinally in said chamber axially thereof, nozzles carried by said pipe in spaced relation to each other longitudinally thereof and in staggered relation to the first mentioned nozzles and having their outer peripheries formed with circumferentially extending outlet slits for discharging thin layers of gas radially of the pipe toward walls of the chamber, and valve controlled means for delivering gas to the pipe and to the first mentioned nozzles.

2. A carbonator comprising a chamber having an inlet and an outlet, nozzles in said chamber between the inlet and outlet spaced from each other longitudinally of the chamber and extending about walls of the chamber and formed with a continuous circumferentially extending outlet slits for discharging thin layers of gas toward the axial center of the chamber transversely of the longitudinal axis thereof, a gas pipe extending longitudinally in said chamber axially thereof, nozzles carried by said pipe in spaced relation to each other longitudinally thereof and in staggered relation to the first mentioned nozzles and having continuous circumferentially extending outlet slits for discharging thin layers of gas radially of the pipe toward side walls of the chamber, a gas main extending longitudinally of the chamber externally thereof and having branches leading transversely therefrom to the upper end of the gas pipe and the first mentioned nozzles, and valves in said branches for individually controlling flow of gas to the first and second mentioned nozzles.

3. A carbonator comprising a casing defining a mixing chamber and having a plurality of superimposed sections and a hollow head provided with an outlet, a base for each section consisting of upper and lower annular members forming an annular nozzle, one member having an inlet and inner peripheral portions of the members

being spaced from each other to provide a circumferentially extending outlet for a thin layer of gas discharged toward the center of the mixing chamber, an inlet tube carried by said head, a gas pipe extending longitudinally in said chamber centrally thereof with its upper end connected with the inlet tube, annular nozzles carried by said pipe within the sections of said casing and each having upper and lower members, the peripheral portions of which are spaced vertically from each other to provide a circumferential outlet for discharging a thin layer of gas toward walls of the casing between and in a direction opposite to travel of gas discharged from the nozzles of the casing, a conduit adapted for connection with a source of gas under pressure, valve controlled connections between said conduit and the tube and between the conduit and the inlets of the first nozzles, and the base for the lower section of said casing having an inlet 20 adapted for connection with a source of liquid to

be carbonated as it flows through the chamber.

4. A carbonator comprising a casing having upper and lower sections defining upper and lower chambers and a throat between the chambers, the lower chamber having an inlet at its bottom and the upper chamber having an outlet at its top, nozzles about the inlet and the throat each having an annular orifice for discharging a horizontal layer of gas toward the vertical axis of the casing, a pipe extending longitudinally in the casing axially thereof, nozzles carried by said pipe in spaced relation to each other longitudinally thereof, the nozzles of said pipe being located in the chambers in spaced relation to upper and lower ends thereof and each formed with annular orifice for discharging a horizontal layer of gas toward sides of the chamber in which the nozzle is located, and means for delivering gas under pressure to the pipe and the first mentioned nozzles.
